PULL-OUT WAND

**CROSS-REFERENCE TO RELATED
APPLICATIONS**

This application is a continuation of U.S. patent application Ser. No. 11/700,556, now U.S. Pat. No. 8,118,240, filed Jan. 31, 2007 and claims the benefit of U.S. Provisional Patent Application Ser. No. 60/794,229, filed Apr. 20, 2006, titled “ELECTRONIC USER INTERFACE FOR ELECTRONIC MIXING OF WATER FOR RESIDENTIAL FAUCETS”, and U.S. Provisional Patent Application Ser. No. 60/793,885, filed Apr. 20, 2006, titled “TOUCH SENSOR”, the disclosures of which are expressly incorporated by reference herein.

**BACKGROUND AND SUMMARY OF THE
INVENTION**

The present invention relates generally to a pull-out wand for use with a faucet or other water delivery device, and in particular to a pull-out wand having one or more sensors coupled to the pull-out wand.

Pull-out wands are known. Further, proximity and touch sensors are known for use with faucets.

In an exemplary embodiment of the present disclosure, a water delivery device in fluid communication with at least one source of water positioned below a mounting deck is provided. The water delivery device comprising a base portion in fluid communication with the at least one source of water and a pull-out wand portion in fluid communication with the base portion. The pull-out wand portion having at least one water output. The pull-out wand portion being moveably between a first position proximate to the base portion and a second position spaced apart from the base portion. The water delivery device further comprising a sensor coupled to the pull-out wand portion and a valve interposed between the at least one water output of the pull-out wand portion and the at least one source of water. The valve being operable to permit communication of water provided by the at least one source of water to the at least one water output of the pull-out wand portion in a first configuration and to prevent communication of water provided by the at least one source of water to the at least one water output in a second configuration. The water delivery device further comprising a controller operably coupled to the sensor and operably coupled to the valve. The controller causes the valve to be in the first configuration in response to a first indication from the sensor.

In another exemplary embodiment of the present disclosure, a pull-out wand for use with a base portion having an associated controller which controls a flow of fluid through the base portion is provided. The pull-out wand comprising a housing moveable between a first position proximate the base portion and a second position spaced apart from the base portion; a waterway within the housing in fluid communication with the base portion; and a sensor supported by the housing. The sensor operably coupled to the associated controller of the base portion.

In a further exemplary embodiment of the present disclosure, a water delivery device for use by a user is provided. The water delivery device being in fluid communication with at least one source of water positioned below a mounting deck. The water delivery device comprising a base portion in fluid communication with the at least one source of water; a pull-out wand portion in fluid communication with the base portion and having at least one water output, a valve interposed between the at least one water output of the pull-out wand

portion and the at least one source of water, an in water sensor adapted to detect if the user is contacting the water exiting the at least one water output of the pull-out wand portion, and a controller operably coupled to the in water sensor and operably coupled to the valve. The pull-out wand portion being moveably between a first position proximate to the base portion and a second position spaced apart from the base portion. The valve being operable to permit communication of water provided by the at least one source of water to the at least one water output of the pull-out wand portion in a first configuration and to prevent communication of water provided by the at least one source of water to the at least one water output in a second configuration. The controller causing the valve to remain in the first configuration in response to the in water sensor detecting the user being in contact with the water exiting the at least one water output of the pull-out wand portion.

Additional features and advantages of the present invention will become apparent to those skilled in the art upon consideration of the following detailed description of the illustrative embodiment exemplifying the best mode of carrying out the invention as presently perceived.

BRIEF DESCRIPTION OF THE DRAWINGS

The detailed description of the drawings particularly refers to the accompanying figures in which:

FIG. 1 is diagrammatic representation of an exemplary water delivery device;

FIG. 2 is a diagrammatic representation of an exemplary embodiment of the pull-out wand of FIG. 1;

FIG. 3 is a perspective view of an exemplary pull-out wand;

FIG. 4 is a side view of the exemplary pull-out wand of FIG. 3;

FIG. 5 is a bottom view of the exemplary pull-out wand of FIG. 3;

FIG. 6 is a perspective view of the exemplary pull-out wand of FIG. 3 having a cover shown in a spaced apart relationship;

FIG. 7 is a perspective view of the exemplary pull-out wand of FIG. 3 illustrating a back portion of the cover;

FIG. 8 is a side view of an exemplary touch sensor; and

FIG. 9 is a representative top view of the touch sensor of FIG. 8.

DETAILED DESCRIPTION OF THE DRAWINGS

The embodiments of the invention described herein are not intended to be exhaustive or to limit the invention to the precise forms disclosed. Rather, the embodiments selected for description have been chosen to enable one skilled in the art to practice the invention. Although the disclosure is described in connection with water, it should be understood that additional types of fluids may be used.

Referring to FIG. 1, a diagrammatic representation of a water delivery device 100 is shown. Water delivery device 100 includes a base portion 102 and a pull-out wand portion 104. Base portion 102 and pull-out wand portion 104 are shown positioned on a first side of a mounting deck 106. Exemplary mounting decks include a countertop, a sink top, a tub, a wall, and other suitable mounting structures.

In one embodiment, water delivery device 100 is a residential kitchen faucet and mounting deck 106 is one of a countertop or a sink. Base portion 102 is a portion of a spout. Pull-out wand portion 104 is a portion of the spout which is moveable relative to the base portion 102 from a first position proximate the base portion 102 to a second position spaced apart from the base portion 102. One or more waterways 103

extend from the base portion 102 to the pull-out wand portion 104 when the pull-out wand portion 104 is in the second position. Exemplary spout base portions and pull-out portions and methods for coupling each are disclosed in U.S. Provisional Patent Application Ser. No. 60/794,229, filed Apr. 20, 2006, titled “ELECTRONIC USER INTERFACE FOR ELECTRONIC MIXING OF WATER FOR RESIDENTIAL FAUCETS”, U.S. Published patent application Ser. No. 11/325,128, Publication No. 20060130907, titled “SPOUT ASSEMBLY FOR AN ELECTRONIC FAUCET,” U.S. Published patent application Ser. No. 11/325,284, Publication No. 20060202142, titled “Method and apparatus for providing strain relief of a cable,” and U.S. Published patent application Ser. No. 11/393,450, Publication No. 20060283511, titled “MAGNETIC COUPLING FOR SPRAYHEADS,” the disclosures of which are expressly incorporated by reference herein.

Base portion 102 is coupled to the mounting deck 106. Pull-out wand portion 104 is coupled to and/or supported by base portion 102. Exemplary couplings between base portion 102 and pull-out wand portion 104 are mechanical couplings, such as o-rings on a docking component, and/or magnetic couplings. In the embodiment illustrated in FIG. 1, base portion 102 is in fluid communication with a mixing valve 108. Mixing valve 108 is in fluid communication with a source of hot water 110 through waterway 111 and a source of cold water 112 through waterway 113. Mixing valve 108 based on an input provided by one or more user inputs 114 regulates the temperature and/or flow of water to base portion 102 through a waterway. In a first configuration, mixing valve 108 prevents the flow of water to base portion 102. In a second configuration, mixing valve 108 permits the flow of water to base portion 102.

In one embodiment, valve 108 provides ON/OFF control. In one embodiment, valve 108 provides ON/OFF control, flow regulation and temperature regulation. In one embodiment, valve 108 is comprised of multiple valves which together provide ON/OFF control, temperature regulation, and/or flow regulation. Exemplary valves are provided in U.S. Provisional Patent Application Ser. No. 60/794,229, filed Apr. 20, 2006, titled “ELECTRONIC USER INTERFACE FOR ELECTRONIC MIXING OF WATER FOR RESIDENTIAL FAUCETS,” U.S. patent application Ser. No. 11/109,281, filed Apr. 19, 2005, titled “ELECTRONIC PROPORTIONING VALVE,” U.S. Provisional Patent Application Ser. No. 60/758,373, filed Jan. 12, 2006, titled “ELECTRONIC MIXING VALVE,” and Patent Cooperation Treaty Patent Application Serial No. PCT/US2006/044023, filed Nov. 13, 2006, titled “INTEGRATED BATHROOM ELECTRONIC SYSTEM,” and the additional patents disclosed herein, the disclosures of which are expressly incorporated by reference herein.

In one embodiment, user inputs 114 directly interact with mixing valve 108, such as a handle coupled to the mixing valve and actuable by a user. In one embodiment user inputs 114 indirectly interact with mixing valve 108, such as by providing one or more inputs to a controller 116. Exemplary inputs to controller 116 include selections made through an electronic user interface, user actuable handles having electrical sensors associated therewith, touch sensors, and/or proximity sensors, such as infrared (IR) sensors and capacitive proximity sensors. Exemplary capacitive proximity sensors are disclosed in U.S. patent application Ser. No. 11/641,574, filed Dec. 19, 2006, titled “MULTI-MODE HANDS FREE AUTOMATIC FAUCET,” U.S. Provisional Patent Application Ser. No. 60/898,524, filed Jan. 31, 2007, titled “HANDS FREE FAUCET UTILIZING NON-CONDUC-

TIVE MATERIALS AND CAPACITIVE SENSORS”, and U.S. Provisional Patent Application Ser. No. 60/898,525, filed Jan. 31, 2007, titled “SINK BASIN CAPACITIVE SENSORS FOR HANDS FREE ACTIVATION OF A FAUCET,” the disclosures of which are expressly incorporated by reference herein. In one example, the range of the capacitive proximity sensor is about 3 inches. Additional details regarding exemplary controllers, electronic user interfaces, user actuable handles, touch sensors, and proximity sensors are provided in U.S. Provisional Patent Application Ser. No. 60/794,229, filed Apr. 20, 2006, titled “ELECTRONIC USER INTERFACE FOR ELECTRONIC MIXING OF WATER FOR RESIDENTIAL FAUCETS”, the disclosure of which is expressly incorporated by reference herein.

Mixing valve 108 and controller 116 are illustrated as being positioned on an opposite side of mounting deck 106 as base portion 102 and pull-out wand portion 104. In one embodiment, one or both of mixing valve 108 and controller 116 are positioned on the same side of mounting deck 106 as base portion 102. In one embodiment, one or both of mixing valve 108 and controller 116 is incorporated into one of base portion 102 and pull-out wand portion 104. Further, in one embodiment, controller 116 includes a first controller positioned in wand portion 104 and a second controller positioned in one of base portion 102 and on an opposite side of mounting deck 106. The first controller positioned in wand portion 104 interfaces with the sensors included in wand portion 104, such as touch sensor 154 and proximity sensor 152 in FIG. 2, and, if included, any user inputs or electrically actuated valves in wand portion 104. The second controller positioned in base portion 102 or on the opposite side of mounting deck 106 interfaces with valve 108 and user inputs 114. The first controller and the second controller being in communication through either a wired or wireless connection. In a wireless connection, such as RF, wand portion 104 includes a battery to power the first controller. In one embodiment, the battery is a rechargeable battery charged with a hydrogenerator disposed in a waterway of wand portion 104.

Referring to FIG. 2, a diagrammatic representation of an embodiment of pull-out wand portion 104 is shown. Pull-out wand portion 104 includes an internal waterway 120 which is in fluid communication with a waterway 103 extending between base portion 102 and pull-out wand portion 104. In one embodiment, waterway 103 and any of the additional waterways disclosed herein are made of a cross-linked polyethylene (PEX) material. In one embodiment, the PEX material is corrugated. In one embodiment, the corrugated PEX material is covered with a braiding layer as described in U.S. patent application Ser. No. 11/700,640, filed Jan. 31, 2007, titled “TUBE ASSEMBLY”, the disclosure of which is expressly incorporated by reference herein.

While in one illustrative embodiment, waterway 103 and any of the additional waterways disclosed herein are made of a cross-linked polyethylene (PEX), it should be appreciated that other polymers may be substituted therefor. For example, waterway 103 and any of the additional waterways disclosed herein may be formed of any polyethylene (PE) (such as raised temperature resistant polyethylene (PE-RT)), polypropylene (PP) (such as polypropylene random (PPR)), or polybutylene (PB). It is further envisioned that waterway 103 and any of the additional waterways disclosed herein could be formed of cross-linked polyvinyl chloride (PVCX) using silane free radical initiators, from cross-linked polyurethane, or cross-linked propylene (XLPP) using peroxide or silane free radical initiators.

Waterway 120 is in further fluid communication with a diverter valve 122. Diverter valve 122 is in fluid communica-

tion with two waterways 124 and 126 which are in fluid communication with a first output 128 and a second output 130, respectively. In one embodiment, first output 128 is configured to provide water in a spray configuration and second output 130 is configured to provide water in a stream configuration.

Divertor valve 122, as is known in the art, diverts the flow of a fluid to one of plurality of potential fluid outlets based on the configuration of the valve. By adjusting the configuration of the valve the fluid outlet that fluid is provided to may be selected. Exemplary divertor valves include manually actuated valves and electrically controlled valves. An exemplary manually actuated divertor valve is a push-button divertor, such as the push-button divertor disclosed in U.S. Provisional Patent Application Ser. No. 60/756,839, filed Jan. 5, 2006, titled "PUSH BUTTON DIVERTER", the disclosure of which is expressly incorporated herein by reference. Exemplary electronically controlled divertor valves include solenoid valves. In one embodiment, an electronically controlled divertor valve is provided in pull-out wand portion 104 and is connected to controller 116 located in one of base portion 102 and the other side of mounting deck 106 through an electrical cable which travels along side of waterway 103. In one embodiment controller 116 includes a first controller and a second controller as discussed herein.

In one embodiment, divertor valve 122 is provided in base portion 102 or on an opposite side of mounting deck 106 as opposed to within pull-out wand portion 104. Since divertor valve 122 would not be positioned within pull-out wand portion 104, two waterways, such as waterways 124 and 126 would extend from base portion 102 to pull-out wand portion 104, each being in fluid communication with a respective outlet of divertor valve 122.

Pull-out wand portion 104 further includes one or more sensors 150. Sensors 150 are operably coupled to controller 116, through either a wired or wireless connection. In one embodiment, one or more of sensors 150 provide an indication of the presence of an object, such as a user's hands or other presentations, in a detection zone. Additional presentations are disclosed in U.S. Provisional Patent Application Ser. No. 60/794,229, filed Apr. 20, 2006, titled "ELECTRONIC USER INTERFACE FOR ELECTRONIC MIXING OF WATER FOR RESIDENTIAL FAUCETS", the disclosure of which has been incorporated by reference herein. In one embodiment, one or more of sensors 150 detect the presence of a touch by a user.

Sensors 150, in one embodiment, include a proximity sensor 152 and at least one touch sensor 154. Proximity sensor 152 monitors a detection zone 156. An exemplary proximity sensor 152 includes an IR emitter which emits IR energy into the detection zone and an IR detector which receives reflected IR energy from the detection zone. When an object, such as a user's hands, is detected in the detection zone, due to the amount of IR energy received by the IR detector, proximity sensor 152 provides an indication to controller 116. In one embodiment, controller 116 monitors a voltage corresponding to the IR level detected by the IR detector to determine when a user's hands are present in the detection zone.

Another exemplary proximity sensor is a capacitive proximity sensor. Exemplary inputs to controller 116 include selections made through an electronic user interface, user actuatable handles having electrical sensors associated therewith, touch sensors, and/or proximity sensors, such as infrared (IR) sensors and capacitive proximity sensors. Exemplary capacitive proximity sensors are disclosed in U.S. patent application Ser. No. 11/641,574, filed Dec. 19, 2006, titled "MULTI-MODE HANDS FREE AUTOMATIC FAUCET,"

U.S. Provisional Patent Application Ser. No. 60/898,524, filed Jan. 31, 2007, titled "HANDS FREE FAUCET UTILIZING NON-CONDUCTIVE MATERIALS AND CAPACITIVE SENSORS," and U.S. Provisional Patent Application Ser. No. 60/898,525, filed Jan. 31, 2007, titled "SINK BASIN CAPACITIVE SENSORS FOR HANDS FREE ACTIVATION OF A FAUCET," the disclosures of which are expressly incorporated by reference herein. In one example, the range of the capacitive proximity sensor is about 3 inches.

10 Touch sensor 154 monitors a region of pull-out wand portion 104 and provides an indication to controller 116 of a user touching that region. In one embodiment, touch sensor 154 is a capacitive sensor. Exemplary touch sensors are further described herein. In one embodiment wherein touch sensor 154 is a capacitive sensor, controller 116 monitors a capacitance of touch sensor 154 to determine when a user touches the region corresponding to the touch sensor 154.

15 Referring to FIGS. 3-9, an exemplary pull-out wand 200 is shown. Referring to FIG. 3, pull-out wand portion 200 includes a housing 202 having a removable cover 204. As shown in FIG. 6, cover 204 includes a tab 206 which is received in an opening 208 of housing 202 and an end face 210 having openings 212 which receive couplers (not shown). The couplers, such as screws, extend through the openings 212 and couple into bosses 214 of housing 202.

20 Bosses 214 are coupled to a sprayhead member 220. Referring to FIG. 5, sprayhead member 220 includes a first, central output 222 and a second, surrounding output 224. In one embodiment, first output 222 provides a stream configuration 30 of water and includes a threaded wall 226 for coupling an aerator assembly. First output 222 being in fluid communication with a first fluid inlet 229. In one embodiment, second output 224 includes a plurality of outlets 228, such as 228A, which are in fluid communication with a second fluid inlet 230. Second output 224 provides a spray configuration.

25 First fluid inlet 229 and second fluid inlet 230 are in fluid communication with waterways 232 and 234 located within housing 202, respectively. Waterways 232 and 234 are in fluid communication with waterways 236 and 238, respectively, 40 which extend back and into a base portion, such as base portion 102. In one embodiment, waterways 232 and 234 are apart of the same tubing as waterways 236 and 238 and are called out separately to highlight their position relative to housing 202.

35 In one embodiment, housing 202 and cover 204 and/or base portion 102 are made of a non-metallic material. Exemplary non-metallic materials include thermoset materials. Exemplary thermoset materials include polyesters, melamine, melamine urea, melamine phenolic, and phenolic.

40 In one embodiment, the waterways described herein including waterways 232, 234, 236, and 238 are made from a cross-linked polyethylene (PEX) material. Additional details about PEX materials and methods for creating a waterway therefrom are found in U.S. patent application Ser. No. 11/700,640, filed Jan. 31, 2007, titled "TUBE ASSEMBLY", the disclosure of which is expressly incorporated by reference herein. In addition, further details regarding PEX materials and methods for creating a fluid transport component therefrom are found in one or more of U.S. Pat. No. 5,895,695, U.S. Pat. No. 6,082,780, U.S. Pat. No. 6,287,501, and U.S. Pat. No. 6,902,210, the disclosures of which are expressly incorporated by reference herein.

45 While in one illustrative embodiment, waterways 232, 234, 236, and 238 and any of the additional waterways disclosed herein are made of a cross-linked polyethylene (PEX), it should be appreciated that other polymers may be substituted therefor. For example, waterways 232, 234, 236, and 238 and

any of the additional waterways disclosed herein may be formed of any polyethylene (PE) (such as raised temperature resistant polyethylene (PE-RT)), polypropylene (PP) (such as polypropylene random (PPR)), or polybutylene (PB). It is further envisioned that waterways 232, 234, 236, and 238 and any of the additional waterways disclosed herein could be formed of cross-linked polyvinyl chloride (PVCX) using silane free radical initiators, from cross-linked polyurethane, or cross-linked propylene (XLPP) using peroxide or silane free radical initiators.

Waterways 236 and 238 are in fluid communication with a diverter valve, such as diverter valve 122. In one embodiment, diverter valve 122 is positioned within housing 202 and a single waterway connects pull-out portion 200 with base portion 102.

Referring to FIG. 5, a proximity sensor 250 is located in a lower portion of housing 202. Sensor 250 includes two windows 252 and 254, through one of which infrared energy is emitted by an IR emitter, such as an LED, and through the other of which infrared energy is received and passed to an IR detector. Although sensor 250 is shown positioned forward of first outlet 222 and second output 224, sensor 250 may be positioned rearward to, to the side of, or between first outlet 222 and second output 224. In one embodiment, a capacitive proximity sensor may be used.

Sensor 250 monitors a detection zone 260 positioned generally below end face 210 of pull-out wand portion 200. In one embodiment, sensor 250 is oriented to monitor a different detection zone, such as forward of, or forward and downward of pull-out wand portion 200.

Referring to FIG. 6, pull-out wand portion 200 includes a plurality of touch sensors 290, 292, 294, 296, and 298. Touch sensors 290 and 292 are slide sensors which monitor the position of a user's finger along a corresponding region 300 and 302 of cover 204, respectively. Additional details concerning slide touch sensors 290 and 292 are provided below and in U.S. Provisional Patent Application Ser. No. 60/793, 885, filed Apr. 20, 2006, titled "TOUCH SENSOR", the disclosure of which is expressly incorporated by reference herein. Touch sensors 294, 296, and 298 monitor a general region of cover 204. Illustratively regions 304, 306, and 308, respectively.

In one embodiment, cover 204 includes indicia to indicate to a user the location of touch sensors 290, 292, 294, 296, and 298 and a function associated with each touch sensor 290, 292, 294, 296, and 298. The function corresponding to the actions taken by controller 116 based on the detection of a touch by a user. Exemplary indicia and the corresponding action taken by a controller relative to a mixing valve and/or diverter valve are provided in U.S. Provisional Patent Application Ser. No. 60/794,229, filed Apr. 20, 2006, titled "ELECTRONIC USER INTERFACE FOR ELECTRONIC MIXING OF WATER FOR RESIDENTIAL FAUCETS".

Cover 204 further includes a window 205 which permits the light generated by indicator devices 320, such as LEDs, mounted to a circuit board 322 to be visible from an exterior of cover 204. In one embodiment, indicator devices 134 indicate a selected parameter of sensor 290. In one embodiment, indicator devices 134 indicate a current value of the parameter controlled by the input to sensor 290.

Tap sensors 294, 296, and 298 may comprise conventional capacitance sensors configured to provide a signal to the controller 116 in response to a user touching the corresponding tap region 304, 306, and 308. Tap sensors 294, 296, and 298 may comprise capacitive touch sensors, such as a Q-Prox™ sensor manufactured by Quantum Research Group of Hamble, United Kingdom. Tap sensors 294, 296, and 298

may operate in a manner similar to that detailed in any one of U.S. patent application Ser. No. 11/325,927, filed Jan. 5, 2006, titled "METHOD AND APPARATUS FOR DETERMINING WHEN HANDS ARE UNDER A FAUCET FOR LAVATORY APPLICATIONS"; U.S. patent application Ser. No. 11/324,901, filed Jan. 4, 2006, titled "BATTERY BOX ASSEMBLY"; U.S. patent application Ser. No. 11/325,128, filed Jan. 4, 2006, titled "SPOUT ASSEMBLY FOR AN ELECTRONIC FAUCET"; U.S. patent application Ser. No. 11/325,284, filed Jan. 4, 2006, titled "METHOD AND APPARATUS FOR PROVIDING STRAIN RELIEF OF A CABLE"; U.S. patent application Ser. No. 11/326,986, filed Jan. 5, 2006, titled "VALVE BODY ASSEMBLY WITH ELECTRONIC SWITCHING"; U.S. patent application Ser. No. 11/326,989, filed Jan. 5, 2006, titled "POSITION-SENSING DETECTOR ARRANGEMENT FOR CONTROLLING A FAUCET"; U.S. Pat. No. 6,962,168, issued Nov. 8, 2005, titled "CAPACITIVE TOUCH ON/OFF CONTROL FOR AN AUTOMATIC RESIDENTIAL FAUCET" U.S. Pat. No. 6,968,860, issued Nov. 29, 2005, titled "RESTRICTED FLOW HANDS-FREE FAUCET" U.S. Published Patent Application 2005/0151101A1, published on Jul. 14, 2005, titled "CONTROL ARRANGEMENT FOR AN AUTOMATIC RESIDENTIAL FAUCET"; and U.S. Published Patent Application 2005/0150556A1, published on Jul. 14, 2005, titled "CONTROL ARRANGEMENT FOR AN AUTOMATIC RESIDENTIAL FAUCET", the disclosures of which are expressly incorporated by reference herein.

As stated above, tap sensors 290 and 292 are slide tap sensors. Referring to FIG. 8, a side view of touch sensor 290 is shown. Touch sensor 292 is the same as touch sensor 290. As such, the following discussion relative to touch sensor 290 is equally applicable to touch sensor 292.

Touch sensor 290 includes a base member 330 having an edge surface or side 332. In one embodiment, base member 330 is generally rigid. In the illustrated embodiment, edge surface 332 has a non-linear profile. In another embodiment, edge surface 332 has a linear profile and/or a combination of one or more linear profile segments and one or more non-linear profile segments. The profile of edge surface 332 may be selected to match a profile of cover 204.

In the illustrated embodiment, base member 330 is a printed circuit board and edge surface 332 is a side of the printed circuit board. The printed circuit board is generally rigid or stiff. Referring to FIG. 9, an exemplary representation of edge surface 332 is shown. Edge surface 332 includes a central portion 334 which is the material of the printed circuit board. Spaced apart top and bottom portions 336A and 336B are made of a conductive material, such as copper. Spaced apart portions 336A and 336B form the capacitive portion of sensor 290. Spaced apart portions 336A and 336B are shown to coincide with a top edge and a bottom edge of edge surface 332. In one embodiment, one or both of portions 336A and 336B may be offset from the respective edge of edge surface 332.

In the illustrated embodiment, the copper of portions 336A and 336B are applied to the printed circuit board such that portions 336A and 336B are a part of edge surface 332. In another embodiment, the copper is not a part of edge surface 332, but is rather backed away from edge surface 332 by an offset amount. In one example, an offset amount of up to about five thousands of an inch. In the illustrated embodiment, edge surface 332 is the material of the printed circuit board. In other embodiments edge surface 332 may be made of other materials.

Touch sensor 290 includes a plurality of leads 338A-F (leads are on both sides of sensor 290) which connect with copper

portions 336A and 336B. These leads are coupled through resistors to two output wires 340A and 340B. Output wires 340A and 340B are coupled to controller 116 which monitors one or more electrical characteristics, such as capacitance, between wires 340A and 340B. As a user brings his or her finger into the area of a portion of edge 332, the capacitance value between wires 340A and 340B is altered. Based on the monitored capacitance value, controller 116 is able to determine the location of a user's finger along edge surface 332.

Controller 116 may detect a rapid touch of an area of edge surface 332 and/or may track the movement of a finger as it slides along edge surface 332. In one embodiment, controller 116 may distinguish between 128 various locations along edge surface 332. As illustrated in FIG. 9, in one embodiment touch sensor 290 may have multiple regions 400 associated therewith, illustratively three regions 402, 404, 406. In operation, controller 116 is capable of distinguishing between a momentary tap in one of regions 402, 404, and 406, and a continuous touch along touch sensor 290. The continuous touch is interpreted as an activation of a slide configuration of touch sensor 290, such as to directly control temperature or flow. The momentary tap is interpreted as an activation of a tap configuration of touch sensor 290 and corresponds to a given function. In the tap configuration regions 402, 404, and 406 of touch sensor 290 operate similar to touch sensors 294, 296, and 298. In one embodiment, indicia are provided on cover 204 to provide a visual cue to the operator of the function associated with regions 402, 404, and 406 of touch sensor 290.

In one embodiment, controller 116 includes the functionality of a Model No. QT401 touch slider integrated circuit or a Model No. QT411 touch slider integrated circuit both available from Quantum Research Group whose North American headquarters are located at 651 Holiday Drive, Bldg. 5/300, Pittsburgh, Pa. and covered under one or more of the following U.S. Pat. Nos. 5,730,165; 6,288,707; 6,377,009; 6,452,514; 6,457,355; 6,466,036; and 6,535,200, the disclosures of which are expressly incorporated by reference herein. In one embodiment, controller 116 utilizes PSOC CAPSENSE technology available from Cypress Semiconductor located at 198 Champion Ct., San Jose, Calif. 95134.

In one embodiment, shielding is used to improve the reliability and performance of touch sensors 290, 292, 294, 296, and 298 which are (in this embodiment) in proximity to metal enclosures of the wand and to in effect make touch sensors 290, 292, 294, 296, and 298 immune to water flowing through the wand. In one embodiment, the shielding techniques used to shield sensors from water flow and to shield sensors from metallic components disclosed in U.S. Provisional Patent Application Ser. No. 60/898,524, filed Jan. 31, 2007, titled "HANDS FREE FAUCET UTILIZING NON-CONDUCTIVE MATERIALS AND CAPACITIVE SENSORS", the disclosure of which is expressly incorporated by reference herein.

Referring to FIG. 7, cover 204 includes three holders 350, 352, and 354. Holders 350 and 354 receive an edge of touch sensors 290 and 292 respectively. Holder 352 receives an edge of circuit board 322. In one embodiment, a wall thickness of cover 204 in the regions corresponding to touch sensors 290 and 292 is generally constant. In one example, the wall thickness is about 0.005 inches. In one embodiment, cover 204 is made of a polymeric material, such as plastic, which has been injection molded.

In one embodiment, pull-out wand 200 is used with a base portion 102 including additional sensors, such as touch sensors and/or proximity sensors. In one embodiment, the base portion includes a faucet handle including a touch sensor.

In one embodiment, controller 116 is connected to sensors 250 through a cable which is positioned along side waterways 236 and 238. Controller 116 is positioned below mounting deck 106. In one embodiment, controller 116 or at least a portion of controller 116 is provided in pull-out wand portion 104.

In one embodiment, a faucet having a pull-out wand may be upgraded. The existing pull-out wand is removed and replaced with pull-out wand 200. A solenoid diverter valve is included under the sink which is in fluid communication with an existing electronic mixing valve. The existing controller is updated to work with sensors 250 of pull-out wand 200.

In one embodiment, an in water sensor 155 is provided in pull-out wand 104. In water sensor 155 detects the presence of a portion of a user in the water stream output by water delivery device 100. In one embodiment, water delivery device 100 provides water at a first flow rate when a user is detected with one of proximity sensor 152 and touch sensor 154, and at a second flow rate when a user is detected with in water sensor 155. In one example, the second flow rate is higher than the first flow rate.

In one embodiment, water delivery device 100 is a faucet and in water sensor 155 detects the presence of the user's hands within an output water stream of the faucet. In one embodiment, in water sensor 155 is a capacitive sensor. Exemplary capacitive sensors for monitoring the presence of a user's hand in the output stream of a faucet are provided in U.S. patent application Ser. No. 11/641,574, filed Dec. 19, 2006, titled "MULTI-MODE HANDS FREE AUTOMATIC FAUCET," U.S. Provisional Patent Application Ser. No. 60/898,524, filed Jan. 31, 2007, titled "HANDS FREE FAUCET UTILIZING NON-CONDUCTIVE MATERIALS AND CAPACITIVE SENSORS", and U.S. Provisional Patent Application Ser. No. 60/898,525, filed Jan. 31, 2007, titled "SINK BASIN CAPACITIVE SENSORS FOR HANDS FREE ACTIVATION OF A FAUCET," the disclosures of which are expressly incorporated by reference herein.

The pull-out wand portions 104, 200 described herein may be incorporated into the water delivery systems, such as faucets, described in U.S. Provisional Patent Application Ser. No. 60/794,229, filed Apr. 20, 2006, titled "ELECTRONIC USER INTERFACE FOR ELECTRONIC MIXING OF WATER FOR RESIDENTIAL FAUCETS", U.S. Pat. No. 6,962,168, U.S. Pat. No. 6,968,860, U.S. Pat. No. 7,150,293, U.S. patent application Ser. No. 11/641,574, filed Dec. 19, 2006, titled "MULTI-MODE HANDS FREE AUTOMATIC FAUCET," U.S. patent application Ser. No. 10/755,582, filed Jan. 12, 2004, titled "CONTROL ARRANGEMENT FOR AN AUTOMATIC RESIDENTIAL FAUCET," U.S. patent application Ser. No. 11/324,901, filed Jan. 4, 2006, titled "BATTERY BOX ASSEMBLY," U.S. patent application Ser. No. 11/326,989, filed Jan. 5, 2006, titled "POSITION-SENSING DETECTOR ARRANGEMENT FOR CONTROLLING A FAUCET" and U.S. patent application Ser. No. 11/326,986, filed Jan. 5, 2006, titled "VALVE BODY ASSEMBLY WITH ELECTRONIC SWITCHING," the disclosures of which are expressly incorporated by reference herein.

Although the invention has been described in detail with reference to certain preferred embodiments, variations and modifications exist within the spirit and scope of the invention as described and defined in the following claims.

The invention claimed is:

1. A water delivery method for delivering water from a hot source of water and a cold source of water, the method comprising the steps of:

11

providing a base portion adapted to be coupled to a hot source of water and a cold source of water;
 mixing water from the hot source of water and the cold source of water to provide a combined water;
 communicating the combined water to at least one water outlet through at least one water conduit;
 supporting a pull-out wand portion with the base portion, the pull-out wand portion being capable of being moved to a spaced apart position relative to the base portion, the least one water conduit being in fluid communication with the least one water outlet which is provided on the pull-out wand portion, the least one water conduit extending between the base portion and the pull-out wand portion when the pull-out wand portion is in the spaced apart position;
 supporting a proximity sensor with the pull-out wand portion;
 supporting a fluid temperature input electronic touch sensor with the pull-out wand portion, the fluid temperature input electronic touch sensor including a plurality of regions extending between opposing ends, the fluid temperature input electronic touch sensor adapted to detect a movement of an object contacting the pull-out wand portion along an exterior of the pull-out wand portion;
 electronically controlling a communication of the combined water to the at least one water outlet of the pull-out wand portion based on an indication received by the proximity sensor; and
 electronically controlling a temperature of the combined water based on a user input received by the fluid temperature input electronic touch sensor supported by the pull-out wand portion, wherein touching different ones of the plurality of regions of the fluid temperature input electronic touch sensor varies the temperature of the combined water.

2. The water delivery method of claim 1, wherein the proximity sensor includes an infrared emitter which emits infrared radiation into a detection zone and a detector configured to receive infrared radiation reflected from the detection zone.

3. The water delivery method of claim 2, wherein the detection zone includes an area below an end face of the pull-out wand portion.

4. The water delivery method of claim 1, wherein the fluid temperature input electronic touch sensor monitors a region of a housing of the pull-out wand portion.

5. The water delivery method of claim 1, wherein the fluid temperature input electronic touch sensor is a slide sensor.

6. The water delivery method of claim 5, further comprising the step of monitoring the slide sensor for the user input.

7. The water delivery method of claim 1, further comprising the step of providing a mixing valve for mixing water from the hot source of water and the cold source of water.

8. The water delivery method of claim 1, further comprising

supporting a third sensor with the pull-out wand portion, the third sensor being spaced apart from the fluid temperature input electronic touch sensor;
 electronically controlling a flow rate of the combined water based on a separate user input received by the third sensor supported by the pull-out wand portion.

9. The water delivery method of claim 8, wherein the fluid temperature input electronic touch sensor controls only temperature and the third sensor controls only flow rate.

10. A water delivery method for delivering water from at least one source of water, the method comprising the steps of:

12

providing a base portion adapted to be coupled to at least one source of water including a hot source of water and a cold source of water;
 mixing water from the hot source of water and the cold source of water to provide a combined water;
 communicating the combined water to at least one water outlet through at least one water conduit;
 supporting a pull-out wand portion with the base portion, the pull-out wand portion being capable of being moved to a spaced apart position relative to the base portion, the least one water conduit being in fluid communication with the least one water outlet which is provided on the pull-out wand portion, the least one water conduit extending between the base portion and the pull-out wand portion when the pull-out wand portion is in the spaced apart position;
 supporting a proximity sensor with the pull-out wand portion;
 supporting a fluid temperature input electronic touch sensor with the pull-out wand portion, the fluid temperature input electronic touch sensor adapted to detect a movement of an object contacting the pull-out wand portion along an exterior of the pull-out wand portion;
 electronically controlling a temperature of the combined water based on a user input received by the fluid temperature input electronic touch sensor supported by the pull-out wand portion;
 wherein the fluid temperature input electronic touch sensor is a slide sensor;
 monitoring the slide sensor for the user input; and
 wherein the slide sensor has a non-linear sensor surface.

11. The water delivery method of claim 10, wherein the pull-out wand portion includes a housing, the housing including a cover and the non-linear sensor surface of the slide sensor having a profile which matches a profile of the cover.

12. A water delivery method for delivering water from a hot source of water and a cold source of water, the method comprising the steps of:

providing a base portion adapted to be coupled to a hot source of water and a cold source of water;
 mixing water from the hot source of water and the cold source of water to provide a combined water;
 communicating the combined water to at least one water outlet through at least one water conduit;
 supporting a pull-out wand portion with the base portion, the pull-out wand portion being capable of being moved to a spaced apart position relative to the base portion, the least one water conduit being in fluid communication with the least one water outlet which is provided on the pull-out wand portion, the least one water conduit extending between the base portion and the pull-out wand portion when the pull-out wand portion is in the spaced apart position;

supporting a first electronic touch sensor with the pull-out wand portion, the first electronic touch sensor including a first plurality of regions extending between opposing ends, the first electronic touch sensor adapted to detect an object contacting the pull-out wand portion along the first plurality of regions of an exterior of the pull-out wand portion;

electronically controlling a temperature of the combined water based on a first user input received at the first plurality of regions by the first electronic touch sensor of the pull-out wand portion, wherein touching different ones of the first plurality of regions of the first electronic touch sensor of the pull-out wand portion varies the temperature of the combined water;

13

supporting a second electronic touch sensor with the pull-out wand portion, the second electronic touch sensor including a second plurality of regions extending between opposing ends, the second electronic touch sensor adapted to detect an object contacting the pull-out wand portion along the second plurality of regions of the exterior of the pull-out wand portion; and electronically controlling a flow rate of the combined water based on a second user input received at the second plurality of regions by the second electronic touch sensor of the pull-out wand portion, the second region being spaced apart from the first region, wherein touching different ones of the second plurality of regions of the second electronic touch sensor of the pull-out wand portion varies the flow rate of the combined water.

13. The water delivery method of claim **12**, further comprising the steps of providing a proximity sensor, and electronically controlling a communication of the combined water to the at least one water outlet of the pull-out wand portion based on an indication received by the proximity sensor.

14. A water delivery method for delivering water from a hot source of water and a cold source of water, the method comprising the steps of:

providing a base portion adapted to be coupled to a hot source of water and a cold source of water; mixing water from the hot source of water and the cold source of water to provide a combined water; communicating the combined water to at least one water outlet through at least one water conduit; supporting a pull-out wand portion with the base portion, the pull-out wand portion being capable of being moved to a spaced apart position relative to the base portion, the least one water conduit being in fluid communication with the least one water outlet which is provided on the pull-out wand portion, the least one water conduit extending between the base portion and the pull-out wand portion when the pull-out wand portion is in the spaced apart position;

14

supporting a proximity sensor with the pull-out wand portion;

supporting a fluid flow rate input electronic touch sensor with the pull-out wand portion, the fluid flow rate input electronic touch sensor including a plurality of regions extending between opposing ends, the fluid flow rate input electronic touch sensor adapted to detect a movement of object contacting the pull-out wand portion along an exterior of the pull-out wand portion;

electronically controlling a communication of the combined water to the at least one water outlet of the pull-out wand portion based on an indication received by the proximity sensor; and

electronically controlling a flow rate of the combined water based on a user input received by the fluid flow rate input electronic touch sensor supported by the pull-out wand portion when the combined water is being communicated to the at least one water outlet of the pull-out portion, wherein touching different ones of the plurality of regions of the fluid flow rate input electronic touch sensor varies the flow rate of the combined water.

15. The water delivery method of claim **14**, further comprising the step of electronically controlling the flow rate of the combined water based on a detection of a user in a water stream from the at least one water outlet.

16. The water delivery method of claim **15**, wherein the flow rate increases in response to the detection of the user in the water stream of the at least one water outlet.

17. The water delivery method of claim **14**, wherein the fluid flow rate input electronic touch sensor is a capacitive touch sensor provided along opposite edges of a rigid base member.

18. The water delivery method of claim **15**, wherein the step of electrically controlling the flow rate of the combined water comprises capacitively sensing when a user is in contact with the water stream from the at least one water outlet.
